UNITED STATES PATENT OFFICE.

CAMBY CLARKE, OF PECK, MICHIGAN.

COMBINATION BOILER AND ROASTER.

1,265,611.

Specification of Letters Patent.

Patented May 7, 1918.

Application filed July 17, 1917. Serial No. 181,099.

To all whom it may concern:

Be it known that I, CAMBY CLARKE, a citizen of the United States, residing at Peck, in the county of Sanilac and State of Michigan, have invented certain new and useful Improvements in Combination Boilers and Roasters; and I do hereby declare the following to be a full, clear, and exact description of the invention, such as will 5 enable others skilled in the art to which it appertains to make and use the same.

This invention relates to a combination boiler and roaster.

The object of my invention is to provide 15 a boiler in which is removably arranged an auxiliary bottom or baffle which prevents the contents when placed within the boiler or roaster from coming in direct contact with the bottom thereof, thus avoiding the 20 same becoming burnt or otherwise ruined.

Another object of this invention is to provide, a boiler or roaster of this character which may be used for preserving, canning, pickling or the like and also may be used 25 for roasting meats, such as fowl, fish or the like and it is equipped with a perforated baffle which is located within the boiler so as to prevent the contents from coming in direct contact with the bottom thereof.

Another object of this invention is to provide 30 a boiler of this type which is equipped with a novel rack adapted to support the boiler away from contact with a stove or other heating source and is also provided 35 with handles whereby the device may be transferred from place to place.

A still further object of this invention is to provide a device of this character, which will be simple, practical and comparatively 40 inexpensive in construction, and one that can be manufactured and sold at a low cost.

With these and other objects in view, the invention consists in the novel combination and arrangement of parts hereinafter more 45 fully described and set forth in the claims hereto appended.

In the drawing:

Figure 1 is a perspective view of the device as made in accordance with this invention.

Fig. 2 is a perspective view of the supporting rack and handles.

Fig. 3 is a perspective view of the baffle or auxiliary bottom, which is adapted to be 55 arranged within the boiler or roaster.

Fig. 4 is a transverse sectional view of the device as a whole.

Like numerals of reference designate corresponding parts in all the figures of the drawing.

Referring to the drawing, the numeral 1 designates a boiler or roaster constructed in accordance with my invention. In its preferred embodiment, the boiler or roaster is oblong and has upwardly and outwardly 60 inclined end and side walls so as to provide a large top portion and a relatively small bottom portion.

The top 2 is adapted to close the upper end of the boiler, and this top is provided 70 centrally of its ends with a handle 3 whereby the top may be raised or lowered from the boiler or roaster. The top is provided on its under side with a depending flange 4, and this flange is located adjacent the 75 peripheral edge of the top and is adapted to engage the inner sides of the side and end walls of the boiler or roaster 1 to prevent the top from shifting thereon. The upper edge of the boiler or roaster is turned 80 back upon itself to provide an exterior retaining bead 5 which is adapted to abut the under side of the top at a point beyond the depending flange so as to prevent the top 85 from slipping down between the side walls.

A perforated baffle 7 has its opposite side edges bent downwardly as at 8, which defines supporting members, and the baffle 7 is of a diameter as great as the bottom of the boiler or roaster 1 and it is adapted to 90 be arranged therein to space the contents placed in the boiler or roaster from contact with the bottom thereof, thus preventing the contents from burning when the same is placed upon a heating source.

A pair of handles 9 are rigidly connected 95 to the end walls of the boiler or roaster 1 as shown in Fig. 1, and when the device is used the handles 9 may be used as guides or may be used for transferring the boiler 100 or roaster from place to place.

A supporting rack, designated by the numeral 10, is formed of a single length of wire looped to provide a pair of longitudinally extending bars which constitute the 105 body of the rack. The bars 11 are crossed centrally, as at 12, and are adapted to be placed in engagement with the under side of the bottom of the boiler or roaster 1 and extend longitudinally thereof. The ends 110

of the bars are bent upwardly as at 13 and crossed centrally as at 14 to provide the substantially inverted U-shaped handles 15. The handles 15 of the rack are adapted to 5 extend upwardly through the guides 9 or the handles of the boiler or roaster 1, thus locating the webs of the handles 15 upwardly beyond the upper surface of the cover 2 which provides means whereby the 10 device may be lifted from and placed upon a heating source.

It can be readily seen that by use of this rack the supporting bars 11 space the bottom of the boiler or roaster from direct contact 15 with the heating source and also avoid the placing of all of the strain upon the rivets or other connections of the handles or guides 9 to the boiler or roaster body when being lifted.

20 It is also to be understood that the handles or guides will prevent lateral shifting movement of the handles of rack 10 and thereby avoid all injury due to the same tilting or twisting when being transferred 25 from the support to the heating source or vice versa.

In use, the member 2 is removed from the boiler or roaster 1 and the baffle is placed therein, as shown in Fig. 4. The side flanges 30 of the baffle engage the side walls of the boiler or roaster, as shown, thus preventing lateral shifting movement of the baffle with relation to the boiler or receptacle 1. The cover is then replaced as shown and the device is grasped by the handles and placed upon the rack 10, the handles of the rack 10 being passed upwardly through the handles or guides 9 and thus the device may be easily and quickly handled while in use.

40 What is claimed is:

1. A boiler or roaster of the class described including a hollow body, a cover removably secured upon said body, a perforated baffle plate located in the body, handles 45 constituting guides secured to the end walls of the body, and a rack removably associated with the body, said rack having its ends

bent upwardly and extended through the guides of the body and beyond the top thereof to permit the device to be lifted as a 50 whole.

2. A boiler or roaster including a hollow body having its upper end fully open, a cover removably secured to the upper open end of the body, handles secured to the end walls of the body, a perforated baffle located in the body, said baffle having downwardly extending side flanges to space the baffle from the bottom of the body, and a rack 55 formed from a single length of wire arranged to provide spaced bars which bars are crossed centrally and have their extreme ends bent upwardly at right angles thereto to form lifting handles, said lifting handles extending through the handles of the body, 60 thereby preventing any lateral shifting movement of the body with relation to the rack.

3. A device of the class described including a hollow body having side walls, a bottom, and end walls, a cover having an annular flange secured to its under side and spaced from the peripheral edge thereof to engage the inner side of the body to hold the cover thereon, handles constituting 75 guides secured to the end walls of the body, a rack formed of a single length of wire comprising spaced bars crossed centrally and the ends of said bars bent upwardly at right angles thereto forming lifting handles which 80 extend through the handles on the end walls of the body and project beyond the top or cover thereof, said handles of the rack locating the spaced bars on the under side of and in engagement with the body to space 85 the bottom of the body a relatively spaced distance from a heating source.

In testimony whereof I affix my signature in presence of two witnesses.

CAMBY CLARKE.
